UNITED STATES PATENT OFFICE.

EDWARD J. KING AND THOMAS R. KENNEDY, OF ROCHESTER, NEW YORK, ASSIGNORS TO THE CO-OPERATIVE FOUNDRY COMPANY, OF SAME PLACE.

DESIGN FOR A HIGH SHELF FOR STOVES.

SPECIFICATION forming part of Design No. 25,155, dated February 11, 1896.

Application filed November 23, 1895. Serial No. 569,963. Term of patent 7 years.

To all whom it may concern:

Be it known that we, EDWARD J. KING and THOMAS R. KENNEDY, of Rochester, in the county of Monroe and State of New York, have invented a certain new and useful Design for the Upper or Shelf Section of Stoves or Ranges; and we do hereby declare the following to be a full, clear, and exact description of the same, taken in connection with the accompanying drawings.

In the drawings, Figure 1 is a perspective view of our design for the upper or shelf section of a stove or range. Fig. 2 is a vertical sectional view. Fig. 3 is a horizontal sectional view taken on the line $x-x$ of Fig. 2, and Fig. 4 is a similar view taken on the line $y-y$ of Fig. 2.

The leading feature of our design consists of the shape and ornamentation of the upper or shelf section adapted to be applied to a stove or range.

The section embodies the central rounded

portion A ornamented, as shown, in relief and having an outlined Maltese cross B in the center. On the sides of this portion A are the lateral plates or wings C having the curved outline and the vine-and-leaf ornamentation thereon in relief, as shown. Projecting from the sides or wings C are the shelves D; but these are not essential to our design, the same general effect being preserved without them.

E indicates the shelf, and above this the panel F ornamented in relief, as shown, with the conventional leaf ornamentation.

What we claim is—

The design for the upper or shelf section of a stove or range, substantially as shown and described.

EDWARD J. KING.
THOMAS R. KENNEDY.
